UNITED STATES PATENT OFFICE

SAMUEL S. MATTHES, OF MANSFIELD, OHIO, ASSIGNEE TO THE OHIO BRASS COMPANY,
OF MANSFIELD, OHIO, A CORPORATION OF NEW JERSEY

CONDUCTOR SUPPORT

Application filed April 7, 1930. Serial No. 442,121.

My invention relates to a steadyng support for trolley conductors and has particular application to such conductors as suspended from the catenary cable.

5 The object of my invention is to provide a device which will prevent side sway of the trolley conductor, but at the same time permit a vertical movement due to the upward pressure of the current collector as it moves along 10 the trolley wire and also to permit a pivotal movement of the clamp for supporting the trolley conductor about a vertical axis such that the trolley clamp will have freedom to move with the trolley wire as it whips side 15 ways, thus relieving to a large degree stress between the trolley wire and the clamp in such cases where the clamp is held rigid with respect to the support.

The preferred embodiment of my invention 20 is described in this specification and shown in the accompanying drawings.

Fig. 1 is a side view of my invention.

Fig. 2 is a top view of the clamp or free end of my invention.

25 Figs. 3 and 4 and 5 are detailed views of the through or clamping bolt which I employ.

I have shown in Fig. 1 my invention as having one end secured to a support 1 by means of a fitting 2 which in turn is secured 30 to the support 1 by the bolts 3. The fitting 2 may have a projecting tongue 4 with a hole therethrough to receive the pin 5. It will be recognized by those skilled in the art that in place of the support 1 as shown the device 35 may be attached to other forms of support common in overhead railway construction.

The trolley conductor 6 is gripped by a clamp 7 comprising jaw member 8 and 9 each provided with lips 10 to grip the conductor 6. The jaws 8 and 9 have abutting members 11 at one end.

45 The jaws 8 and 9 are provided with transverse registering holes between their upper and lower edges to receive the through bolt 12 shown in detail in Figs. 3, 4 and 5 and which comprises a stud portion 13 with a threaded end 14 to receive the nut 15 and a socket portion 16 having a passage 17 therethrough. When the through bolt is positioned relative to the jaws 8 and 9 and the

nut 15 drawn up, the jaws will be forced into tight engagement with the trolley conductor 6 and the abutting portions 11 will also be forced into contact and will act as a fulcrum point for the jaws. If desired 55 a spring lock washer 18 may be used.

The clamp 17 is supported by means of the steady rod 19 which is shown as comprising a metal member 20 having a bent end portion 21 which is positioned in the vertically disposed passage 17 in the bolt 12 and is prevented from vertical displacement by means of the overhanging lip 22 on the jaw 8. This construction will maintain the clamp 7 and the steady rod 19 in assembled relation such that the clamp will swivel in a horizontal plane relative to the steady rod 19 and will move in a vertical plane with the member 19 as the member 19 pivots about the pin 5. 60

The rod 20 is shown as secured to a strain insulator 23 which comprises an end cap 24 having a clevis portion 25 secured to the tongue 4 by means of the pin 5 and also an end cap 26 having a threaded portion 27 secured to the threaded end 28 of the rod 20. 75 The end caps 24 and 26 are connected by means of the insulating member 29 which may be of wood or other suitable insulating material.

80 The member 29 may have tapering end portions upon which the caps 24 and 26 are compressed or the caps and end portions of the member 29 may be threaded together or they may be secured in other approved manner. In assembling the rod 20 to the clamp 7 the bent end 21 is positioned in the passage 17 before the member 12 is positioned with respect to the jaws 8 and 9.

I prefer to have the longitudinal axis of the arm 19 angularly disposed to the vertical plane common to the trolley wire holder 7 and the trolley wire 6, thus giving greater clearance between the arm 19 and the outer end of a moving bow or pantograph current collector. 90

95 Modifications of course will be apparent to those skilled in the art, but I wish to be limited only by my claims.

I claim:

100 1. A steady device comprising an elongated

arm having means to secure one end of the arm to a support, holding means at the other end to hold a wire, means on the holding means projecting sideways therefrom to slidably receive the end of the arm and projecting means on the holding means to engage the arm and prevent separation after assembly and in use.

2. A conductor support comprising means to receive and hold a conductor, transverse means secured to the conductor-holding means to hold the jaws clamped to the conductor, transverse passage in the transverse holding means and having an axis transverse to the conductor axis and a support mounted in the passage to pivot about its axis and projecting means on the conductor-holding means to co-operate with the support to prevent separation of the support and holding means after assembly of the parts.

3. A conductor support comprising clamping means to engage and hold a conductor comprising a pair of jaws, transverse means to hold the jaws clamped to the conductor, transverse passage in the transverse holding means and having an axis transverse to the conductor axis and a support mounted in the passage to pivot about its axis and means on one of the jaws to co-operate with the support to prevent separation of the support and clamping means after the parts are assembled.

4. A conductor support comprising a pair of jaws having means to grip a conductor, a transverse holding member having an enlarged head on one end with a transverse passage therein to receive a support in pivotal relation thereto and a threaded nut on the other end to draw and maintain the jaws in clamped relation to the conductor and projecting means on one jaw spaced from the said head and overhanging to prevent the removal of the support.

5. A conductor support comprising a clamping means to engage a conductor consisting of a pair of jaws with means to engage and hold the conductor, means to draw the jaws into said engagement with the conductor and means on the last said means to receive a support and other means to prevent separation of the support and clamping means.

6. A conductor support comprising a pair of jaws to grip a conductor, transverse means to hold the jaws to the conductor, means on the transverse means to receive a supporting member in pivotal relation to one of the jaws and projecting means on one of the jaws and spaced from the transverse means to prevent separation of the support and supporting means.

7. A conductor support comprising a pair of jaws to grip a conductor, transverse means to hold the jaws to the conductor, means on the transverse means to receive a support

member in pivotal relation to the support about an axis at right angles to the axis of the conductor and means to prevent separation of the supporting member and the support.

8. A trolley device comprising an arm with means at one end to be secured to a support, the arm having its other end bent at an angle to the axis of the arm, an elongated holding member mounted on the bent end portion of the arm to pivot about the axis of the said bent portion and having a threaded end, a pair of clamping jaws mounted on the holding member and having lips to grip a trolley conductor, means on the holding member to draw the jaws into holding engagement with the conductor and means on one jaw to engage the arm at the bight to prevent disengagement of the arm from the holding member.

9. A trolley device comprising a pair of jaws, a through bolt to draw the jaws into holding engagement with a conductor, an arm projecting from one of the jaws at an inclined angle and having means at one end to secure it to a support, means on the other end of the arm to secure it to said jaw to permit the jaws to pivot about a vertical axis relative to the arm but held against pivotal movement relative to the arm about a horizontal axis.

10. A steady device comprising an elongated laterally projecting arm, means at one end to pivotally secure the arm to a support, holding means at the other end to receive and hold a conductor and means securing the arm and holding means together intermediate the upper and lower edges of the holding means and permit the holding means to swivel relative to the arm in the plane of the conductor and maintain the holding means against movement relative to the arm in a plane transverse to the conductor and means on the holding means to engage means on the arm to prevent accidental removal of the holding means from the arm.

11. A steady device comprising an elongated arm, means at one end to secure the arm to a support, holding means at the other end to receive and hold a conductor and means transversely disposed relative to the holding means securing the holding means directly to the arm with the longitudinal axis of the arm angularly disposed to the vertical plane of the holding means and conductor and permit the holding means to swivel relative to the arm in the plane of the conductor and maintain the holding means against movement relative to the arm in a plane transverse to the conductor and means to prevent accidental removal of the holding means from the arm.

12. A steady device comprising an insulated elongated arm having means to attach one end to a support, holding means at the

- other end to receive and hold a conductor, means projecting from the holding means from a point between its upper and lower edges for securing the arm and holding
5 means together with the arm extending in a transverse direction from the holding means and means on the holding means to prevent accidental separation of the holding means and arm.
10 13. A steady device comprising an elongated arm, means at one end to secure the arm to a support and the other end of the arm having a bent portion, holding means at the other end of the arm and attached to
15 the bent portion to grip a conductor and means projecting from the holding means between its upper and lower edges to secure the holding means to the arm and means on the holding means to engage the end of the
20 arm to prevent detachment of the arm.

In testimony whereof I affix my signature.
SAMUEL S. MATTHES.
